UNITED STATES PATENT OFFICE.

FRANCIS J. TORRANCE, OF ALLEGHENY, PENNSYLVANIA.

DESIGN FOR A BATH-TUB.

SPECIFICATION forming part of Design No. 18,949, dated March 5, 1889.

Application filed February 9, 1889. Serial No. 299,299. Term of patent 14 years.

To all whom it may concern:

Be it known that I, FRANCIS J. TORRANCE, a citizen of the United States, residing at Allegheny, in the county of Allegheny and State of Pennsylvania, have invented a certain new Design for a Bath-Tub; and I do hereby declare the following to be a full, clear, and exact description of the invention, reference being had to the accompanying drawings, which form part of this specification.

My invention has relation to designs for stationary bath-tubs; and it consists in the provision of a bath-tub of a novel configuration or shape, ornamented in a new and tasteful manner.

Referring to the accompanying drawings, Figure 1 is a perspective, Fig. 2 a longitudinal sectional view, and Fig. 3 a vertical sectional view, of a bath-tub embodying my design.

As seen from above, the tub is of a parallelogrammic form, having four sides, A A, &c., joined by rounded corners a a, &c. The sides A A converge toward the bottom B and are joined thereto by rounded edges c c. The bottom D slants from all its edges toward a point, E, which is at or near the center of the bottom, and at this point is situated the drain-passage F, which communicates with the drain-discharge E at one side of the center of the bottom. The tub proper is mounted upon four legs, f f f f, situated two on each side of the bottom of the tub. Each of these

is broad at the top and narrow at the bottom, where it ends in a reversed upward curved foot-piece, g, the sides being flanged and ornamented with flutes i i, &c., and cross-bands j j, the whole forming a pleasing and artistic foot or pedestal.

The top of the tub is furnished with a broad flat rim following the outline of the four sides and the rounded corners.

The whole tub, as seen, is devoid of any sharp corners or angles, and is therefore soft and pleasing to the eye of the observer, and does not offend the most rigorous artistic taste.

The leading and prominent feature of the design is the outline of the four sides converging toward the bottom and having rounded corners and lower edges and the bottom slanting toward a central point from all its edges, the whole surrounded by the broad flat upper edge and mounted on the side flanged and ornamented legs.

What I claim is—

The design for a stationary bath-tub herein described and illustrated.

In testimony that I claim the foregoing I have hereunto set my hand this 26th day of January, 1889.

FRANCIS J. TORRANCE.
